UNITED STATES PATENT OFFICE.

GEORGE X. WENDLING, OF SAN FRANCISCO, CALIFORNIA.

SQUARE-END NAIL OR STAPLE.

Application filed May 16, 1923. Serial No. 639,368.

To all whom it may concern:

Be it known that I, GEORGE X. WENDLING, a citizen of the United States, residing at the city and county of San Francisco and State of California, have invented certain new and useful Improvements in Square-End Nails or Staples, of which the following is a specification.

It has been discovered in the handling of flinty and splitty woods, particularly the hard heavily grained woods, that in driving nails of the present type thereinto the same are deflected through the side of the material while being driven fully home, and in the majority of instances cause a splitting of the wood. It has also been discovered that the tapered point iron or wire nails and the machine pointed end wire nails either of the single shank or staple type, when driven into thin veneer like sheets of flinty or splitty structure, often split the same unless the wood is green or water soaked prior to the nailing operation. This previous preparation of the wood prior to its nailing renders the same difficult to handle and causes serious warping and splitting when the wood dries. Wire nails and staples of the wedge pointed type when driven into the wood tend to separate the grain, which is occasioned by the point serving as a wedge to facilitate the easy driving of the nail.

My present invention relates to a nail either of the single or double shank type which when driven into wood acts as a punch and cuts its own path and does not in any manner tend to split or separate the grain of the wood in its passage therethrough. It has been discovered that in the nailing of veneer like wood, of coarse grain or flinty nature, a wire nail or staple, the end of which is cut at right angles to the walls will, when driven, act as a punch and cut its own path through the material, this being accomplished by the annular cutting edge at the lower free end of the nail or staple. It has also been discovered that this cutting action may be increased by making the terminal end of the shank concave.

With the above mentioned and other objects in view, the invention consists in the novel construction and combination of parts hereinafter described, illustrated in the accompanying drawings, and set forth in the claim hereto appended, it being understood

that various changes in the form, proportion, size and minor details of construction within the scope of the claim may be resorted to without departing from the spirit or sacrificing any of the advantages of the invention.

To more fully comprehend the invention reference is directed to the accompanying drawings, wherein:—

Fig. 1 is a view in elevation of a staple having an end of my improved type.

Fig. 2 is a view in end elevation of the staple illustrated in Fig. 1.

Fig. 3 is a view illustrating the end with the concave depression.

Fig. 4 illustrates a nail made in accordance with my invention.

Fig. 5 is an end view thereof.

Fig. 6 is a view showing the end concave.

Referring more particularly to the several views of the drawings wherein like characters of reference designate corresponding parts, 1 indicates the parallel prongs of a wire staple connected by the bridle 2. As illustrated, the walls of the prongs are parallel and the lower end in elevation is cut at right angles to the walls as at 3 affording at its periphery an annular cutting edge 4. This cutting edge may be further accentuated by concaving the end 3 of the prongs 1 as at 5, which provides an annular knife edge 6 at the base of each prong.

As in Fig. 4, a wire nail 7 may be provided with a blunt end 8 cut at right angles to the side walls to receive an annular cutting edge 9 at the lower end of the nail and this, like the staple prongs, may be concaved as at 10.

In the manufacture of staples in accordance with my present invention, the pointing of the same is dispensed with, and it is feasible to employ wire and merely shear the same straight through prior to bending the length thereof into staple formation.

Having thus described my invention, what I claim as new and desire to protect by Letters Patent of the United States is:—

A nail for driving into wood for securing purposes comprising a head and rigid elongated shank of relatively small diameter, the lower or driving end of the shank being dished to provide a sharp peripheral cutting edge of the same circumference as the shank.

In testimony whereof I have signed my name to this specification.

GEORGE X. WENDLING.
